United States Patent Office

Des. 228,456
Patented Sept. 25, 1973

228,456

PHARMACEUTICAL TABLET

Fred C. Ninger, Morristown, N.J., assignor to Warner-Lambert Company, Morris Plains, N.J.

Filed Dec. 13, 1971, Ser. No. 207,710

Term of patent 14 years

Int. Cl. D28—01

U.S. Cl. D16—3

Fig. 1.

Fig. 2.

Fig. 3.

Fig. 4.

Fig. 5.

Fig. 6.

FIG. 1 is a view in perspective of a pharmaceutical tablet embodying my new design;

FIG. 2 is a top plan view thereof;

FIG. 3 is a view of the underside of the plan view of FIG. 2;

FIG. 4 is a side-elevational view thereof;

FIG. 5 is an end view thereof, taken 90° from the side view of FIG. 4;

FIG. 6 is a cross sectional view thereof, taken along line 6—6 of FIG. 2.

I claim:

The ornamental design for a pharmaceutical tablet, substantially as shown.
